UNITED STATES PATENT OFFICE.

WALTER PAYNE HIMES, OF NEW BETHLEHEM, PENNSYLVANIA, ASSIGNOR OF ONE-HALF TO LESLIE R. HIMES, OF NEW BETHLEHEM, PENNSYLVANIA.

SHOWCASE.

1,376,203.

Specification of Letters Patent. Patented Apr. 26, 1921.

Application filed March 29, 1920. Serial No. 369,493.

To all whom it may concern:

Be it known that I, WALTER PAYNE HIMES, a citizen of the United States, and a resident of New Bethlehem, in the county 5 of Clarion and State of Pennsylvania, have invented a new and Improved Showcase, of which the following is a full, clear, and exact description.

The invention relates to store furniture 10 and its object is to provide a new and improved show or display case more especially designed to be set against a wall and which is exceedingly strong and durable in construction and practically moistureproof.

Another object is to permit of readily assembling the parts in the manufacture of 15 the show case.

With these and other objects in view, the invention consists of certain novel features 20 of construction as hereinafter shown and described and then specifically pointed out in the claims.

A practical embodiment of the invention is represented in the accompanying drawings 25 forming a part of this specification, in which similar characters of reference indicate corresponding parts in all the views.

Figure 1 is a front elevation of the improved show case;

Fig. 2 is a side elevation of the same;

Fig. 3 is an enlarged cross section of the same on the line 3—3 of Fig. 1;

Fig. 4 is a similar view of a portion of the upper or shelf compartment of the show 35 case, the section being on the line 4—4 of Fig. 1;

Fig. 5 is an enlarged sectional plan view of the improved show case, the section being on the line 5—5 of Fig. 3;

Fig. 6 is a similar view of the same on the line 6—6 of Fig. 3;

Fig. 7 is a similar view of the same on the line 7—7 of Fig. 1;

Fig. 8 is an enlarged sectional front elevation of the improved show case on the line 8—8 of Fig. 3;

Fig. 9 is a perspective view of one of the sides of the lower compartment; and

Fig. 10 is a sectional plan view of the 50 joint connecting two show cases with each other.

The improved show case in its general construction consists of a base 10, a lower compartment 11 and an upper or shelf compartment 12 set on top of the lower com-

partment 11. The base 10 is in the form of a hollow box-like structure, open at the top and bottom and comprising a sheet metal front 15, a sheet metal back 16 (see Fig. 3) and sheet metal sides 17 (see Fig. 8). The front, back and sides of the base 10 are provided with inwardly turned flanges 18, 19 and 20 for supporting the base on a floor or other suitable support, and to the front 15 and the sides 17 are fastened slabs 65 25, 25 of marble or other suitable material, preferably by the use of bolts 27, as plainly shown in Figs. 1, 2 and 3.

The upper ends of the front 15, back 16 and sides 17 are provided with inwardly turned flanges 30, 31 and 32, and on the flanges 31 and 32 rests the bottom 40 of the lower compartment 11 and which bottom forms the top for the base 10. A bottom plate 41 overlies the front flange 30 and this bottom plate 41 is spaced from the bottom 40 to provide a sidewise extending slot 42. The bottom plate 41 is provided with an angular flange 43 extending over the outer face of the upper portion of the front 80 15, and this flange 43 is fastened in place with the upper row of bolts 27 used for fastening the front slab 25 to the front 15.

The lower compartment 11 is open at the front and is formed of the sides 50 and the 85 back 51 of sheet metal and having inturned flanges 52 and 53 (see Figs. 3 and 8) of which the flanges 52 rest on the flanges 32 while the flanges 53 rest on the bottom 40. The backs 16 and 51 and their flanges 31 90 and 53 are reinforced by angle irons 54, 55 fastened to the back 16 by bolts 56, 57 or similar fastening means, and bolts 58 connect the angle irons 54, 55 with each other and pass through the flanges 31 and 53 and 95 the bottom 40 to firmly secure the lower compartment 11 to the base 10. The upper end of each side 50 is provided with an inwardly turned flange 60 terminating in a downwardly extending flange 61 from 100 which extends outwardly a flange 62, as plainly indicated in Fig. 8. Between the inner flanges 61 of the two sides 50 extends a top 65, preferably in the form of a glass plate, to close the top of the lower compartment 11. The open front of the lower compartment 11 is adapted to be closed by two sliding doors 70 and 71 each preferably made of a single sheet of glass of sufficient thickness to dispense with frames for 110

the same. The doors 70 and 71 are provided on the front face near their outer edges with recesses 72, 73 forming finger holds for conveniently sliding the doors into 5 open or closed position. The doors 70 and 71 are inclined upwardly and rearwardly and their lower ends extend through the slot 42 and rest on a track formed of two sets of rollers 74, 75 mounted to turn on rivets or 10 bolts 76 attached to angle irons 77 and 78, of which the angle iron 77 is secured by bolts 79 to the under side of the top flange 30 and the plate 41, as plainly shown in Fig. 3. The angle iron 78 is fastened to 15 the front margin of the bottom 40 by bolts 80. The sets of rollers 74, 75 are spaced apart by division plates 81 held on the rivets 76. When the doors 70 and 71 are in closed position, as shown in Fig. 1, then their adjacent inner sides slightly overlap to 20 completely close the front open end of the lower compartment 11. In order to open the door 70 the latter is moved to the right and in order to open the door 71 the latter is moved 25 to the left. The upper ends of the doors 70 and 71 engage a guideway formed by two angle irons 90 and 91 having end flanges 92 and 93 fastened by bolts 94, 95 to the inner flanges 61 of the sides 50. By reference to Fig. 3 it will be noticed that the upper 30 ends of the doors 70 and 71 are a distance below the top of the guideway to allow of conveniently inserting the doors or removing the same whenever it is desired to do so. In order to hold the upper ends of the doors 70 and 71 spaced apart use is made of a partition 100 formed of a piece of doubled-up sheet metal 101 extending around the angle iron 90 and secured thereto 40 by screws 102 or other suitable fastening devices. A similar piece of metal 105 covers the front portion of the angle iron 91 and extends over the top thereof to abut with its inner edge against the partition 100. This piece of metal 105 is fastened in place 45 on the angle iron 91 by screws 106 or similar fastening devices. It will be noticed that by the arrangement described the doors 70 and 71 can be easily moved into open or closed position without danger of binding and the doors are held properly spaced apart by the division plates 81 and 100 at the track and guideways respectively. A piece 107 of felt or other suitable material 50 is preferably interposed between the top 65 and the metal pieces 101, 105 to provide a cushioning seat for the glass top 65. Bumpers 108 are secured to the sides 50 at the ends of the glass doors 70 and 71 to cushion the latter when in closed position.

The upper end of the back 51 is provided with an inwardly extending flange 110 reinforced by an angle iron 111 fastened in place by bolts 112 and 113, of which the 65 bolts 113 also engage an angle iron 114 at-

tached to the back 115 of the upper compartment 12 to fasten the latter in position on top of the lower compartment 11. Bolts 116 serve to fasten the angle iron 114 to the back 115. On the back 51 is arranged a 70 mirror 120 engaged at the front and back by cushioning strips 121 and 122, of felt or other suitable material, and the said mirror 120 is held in place by a metal frame 125, the individual members of which are fastened by the bolts 57 and 112 to the angle irons 53 and 111. The top member of the frame 125 is provided with an extension 126 fastened by the bolt 113 to the angle iron 111, and this extension 126 supports a felt 75 strip 127 on which the rear end of the glass top 65 rests. The sides 50 of the lower compartment 11 are preferably provided with 80 openings 130, each closed by a glass panel 131 mounted in a suitable frame 132 fastened to flanges 133 forming the wall of the corresponding opening 130 (see Fig. 7). By the use of the glass doors 70 and 71, the glass top 65 and the glass panels 131 the interior of the lower compartment 11 is effectively illuminated. 85

The upper compartment 12 is provided at each side with front and rear tubular legs 140 and 141 (see Figs. 3 and 6) resting on the top flanges 60 of the sides 50 of the lower compartment 11, and the said legs 140 and 141 form integral parts of the two sides 142 of the upper compartment 12. The rear ends of the sides 142 are provided with flanges overlying the sides of the back 115 95 and fastened thereto by bolts 144 or other fastening devices. The upper compartment 12 is provided with a bottom 150 fastened at its rear end by bolts 151 to an angle iron 152 secured by bolts 153 to the back 115, and the front of the bottom 150 is secured by bolts 155 to an angle iron 156 having end flanges 157 fastened by bolts 158 to the sides 142 (see dotted lines in Fig. 5). The angle iron 156 forms with a similar angle 100 iron 160 a portion of a track having sets of rollers 161, 162 mounted to turn on rivets 163 connecting the angle irons with each other. The friction rollers 161, 162 are spaced apart by a division plate 164 held on 105 the rivets 163. The track is inclosed in a cover 165 attached by bolts 166 to the angle iron 160 and attached by bolts 155 to the angle iron 156, as plainly shown in Fig. 3. A covering plate 167 extends under the bottom 110 150 and is fastened in place by the bolts 151 and 155 (see Fig. 8). Bumpers 169 are attached to the sides 142 for cushioning the 115 ends of the sliding doors 170 and 171 (see Fig. 5). It will be noticed that the bottom 120 150 forms with the top of the covering 165 a slot 168 through which extend the lower 125 ends of the sliding doors 170 and 171 for opening and closing the front of the upper compartment 12. The doors 170 and 171 130

are each of a single piece of glass, similar to the doors 70 and 71 for the lower compartment 11. The upper ends of the doors 170 and 171 extend into guideways 172 and 173 struck up from the top 175 of the upper compartment 12, the said top 175 being attached at its rear end by bolts 176 to an angle iron 177 fastened by bolts 178 to the back 115. The front of the bottom 175 terminates in a downwardly extending cornice supporting plate 180 and the front end of the top 175 and the plate 180 are reinforced by an angle iron 181 fastened in place by bolts 182 and 183, of which the bolts 183 also serve to fasten the cornice 184 in position on the front plate 180. The cornice 184 fits between the upper portions of the sides 142. By reference to Fig. 3 it will be noticed that the guideways 172, 173 are of sufficient height to permit of lifting the doors 170 and 171 to raise the lower ends thereof out of the slot 167 whenever it is desired to remove the doors 170 and 171 from the upper compartment 12 or to place the said doors in position on the said compartment.

The upper compartment 12 is preferably provided with glass shelves 190 mounted on brackets 191 fastened by bolts or other fastening devices 192 to the back 115, as plainly shown in Fig. 4. The back 115 of the upper compartment 12 is provided intermediate the top 65 and the bottom 150 with a mirror 200 engaged along its margin by felt front and rear strips 201, 202, and fastened in place by a metal frame 203 secured in position by the bolts 116 and 153 (see Fig. 3).

When it is desired to join two show cases then one of the sides of the lower and upper compartments of one show case is omitted, and the two cases are fastened together, as indicated in Fig. 10, by the use of suitable bolts 300 with a joint covering strip 301 at the back.

From the foregoing it will be seen that by the arrangement described the show case is made only of metal and glass without any woodwork whatever, and an exceedingly strong and durable construction is provided.

It will also be noticed that the several parts can be readily manufactured and assembled.

Having thus described my invention, I claim as new and desire to secure by Letters Patent:—

1. A show case, comprising a hollow metal base, a lower compartment attached to the base and made of metal, the said lower compartment having sliding glass doors at the front and glass panels at the sides to illuminate the interior of the compartment, and an upper metal compartment having hollow legs resting on the sides of the said lower compartment, the said upper compartment having sliding glass doors at the front.

2. A show case, comprising a hollow base,

a lower compartment attached to the base and having sliding glass doors at the front and glass panels in its sides, and an upper compartment having legs resting upon the lower compartment and having sliding glass doors at the front, the said doors being in rear of the front legs.

3. A show case, comprising a hollow metal base, a lower compartment attached to the base and provided with a glass top and with sliding doors at the front, each door being formed of a single glass plate, and an upper compartment having side legs resting on the lower compartment to space the upper compartment from the glass top, the said upper compartment being provided at the front with sliding doors each formed of a single glass plate.

4. A show case, comprising a hollow base, a bottom compartment attached to the said base and having its bottom, sides and back made of sheet metal, the bottom forming the top of the said base, the said bottom compartment having a glass top and having glass sliding doors at the front, a track attached to the under side of the said bottom and the said sides and having sets of rollers for the bottom edges of the doors to slide on, and guideways underneath the glass top and attached to the said sides of the lower compartment, the said guideways being slidably engaged by the upper ends of the said glass doors.

5. A show case, comprising a hollow base, and a compartment attached to the said base and having a bottom forming the top of the base, the said bottom having a sidewise extending slot, a track attached to the under side of the bottom, sliding doors for closing the front of the compartment and extending through the said slot and engaging the said track, and guideways in the top portion of the compartment and engaged by the upper ends of the doors.

6. In a show case, a compartment having metal sides, a metal bottom provided with a sidewise extending slot, a metal top and a metal back, the compartment having front and rear metal legs, a double track attached to the under side of the said bottom and extending along the said slot, the said top being formed into spaced guideways extending upward from the top, and glass doors slidably engaging the said track and the said guideways.

7. In a show case, a compartment having metal sides, a metal bottom provided with a sidewise extending slot, a metal top and a metal back, the compartment having front and rear legs, a double track attached to the under side of the said bottom and extending along the said slot, the said top being bent to form into spaced guideways extending upward from the top, the said track having sets of rollers and a spacing

plate separating the sets of rollers, and glass doors slidably engaging the said track and the said guideways.

8. A show case, comprising a metal base, 5 a lower metal compartment attached to the base, and having a glass top, sliding glass doors at the front, glass panels in the sides,

and a mirror in the back, and an upper metal compartment having legs resting on the sides of the lower compartment and having 10 sliding glass doors, the back of the upper compartment extending below the compartment and having a mirror therein.

WALTER PAYNE HIMES.
